UNITED STATES PATENT OFFICE.

NICHOLAS BIER, OF SALEM, OREGON.

DESIGN FOR A LAST.

SPECIFICATION forming part of Design No. 23,733, dated October 23, 1894.

Application filed September 19, 1894. Serial No. 523,499. Term of patent 7 years.

To all whom it may concern:

Be it known that I, NICHOLAS BIER, a citizen of the United States, residing at Salem, in the county of Marion and State of Oregon, have 5 invented and produced a new and original Design for a Last, of which the following is a specification, reference being had to the accompanying drawings, forming part thereof, in which—

10 Figure 1 is a side elevation of a last embodying my new design; and Fig. 2 is a plan view of the same.

The leading feature of my design consists of the novel configuration of the foot portions 15 and of the central shank, the bottom surface of one foot portion being uppermost and the corresponding surface of the opposite foot

portion being lowermost, such bottom surfaces at their inner ends terminating in about the same vertical plane, and presenting each 20 a contraction as at *a*, adjacent to but slightly removed from the inner terminal, and such inner terminals each joining at an angle the curved inner ends *b* of the top surface of the opposite foot portion; the shank, as seen in 25 side view, being disposed at only a slight angle to the vertical.

I claim—

The design for a last herein shown and described.

NICHOLAS BIER.
